UNITED STATES PATENT OFFICE.

CHARLES UHDIEN AND IRA OWEN, OF SPOKANE, WASHINGTON.

MATTRESS ATTACHMENT.

No. 892,334.

Specification of Letters Patent. Patented June 30, 1908.

Application filed August 6, 1907. Serial No. 387,315.

To all whom it may concern:

Be it known that we, CHARLES UHDIEN and IRA OWEN, both citizens of the United States, and residents of Spokane, in the county of Spokane and State of Washington, have invented a new and Improved Mattress Attachment, of which the following is a full, clear, and exact description.

This invention relates to mattress attachments and is particularly useful as a bolster in connection with a mattress body.

An object of the invention is to provide a simple, strong and inexpensive attachment or bolster adapted to be secured removably to a mattress and serving as a protector for the feet, and for holding the covers of a bed in position at the foot thereof.

A further object of the invention is to provide a device of the class described having a removable bolster adapted to serve as a foot protector, or as a bolster for the head.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which

Figure 1 shows a side elevation of a mattress having our invention applied thereto and showing the same in a different position in dotted outline; Fig. 2 is a perspective view of a bed showing a mattress thereupon with our invention applied thereto; and Fig. 3 is a longitudinal section of a mattress provided with our invention, showing parts broken away.

Before proceeding to a more detailed explanation of our invention it should be clearly understood that the attachment, comprising essentially a bolster, is primarily intended as a foot protector, to keep the feet of the occupant of the bed warm and to protect them from drafts and other currents of cold air, while at the same time serving firmly to hold the covers in position at the foot of the mattress. The invention is also adapted to be used as a bolster and for the purposes for which a bolster is usually employed, for instance, as a head support or a support for the pillows when the bed is not in use. The bolster is removably secured to the mattress at an end thereof and if so desired two bolsters may be employed, one

mounted at each end of the mattress. The connection between the bolster and the mattress is flexible and the points of attachment of the mattress and the bolster are between adjacent edges of each. As appears most clearly in Fig. 1, the operative position of the bolster is at substantially right-angles with the mattress body, one side of the bolster resting upon the upper surface of the mattress near one end of the same. In this position the mattress protects the feet of the occupant of bed and holds the covers, the ends of which are inserted between the mattress and the bolster, securely in position. If so desired, the bolster may be folded back upon the mattress in a position substantially parallel with the length thereof. In the latter position the bolster may be used as a head rest or for the purposes indicated by the generic term "bolster". It will be understood that the bolster may be used as a head protector in exactly the same manner as it can be used for protecting the feet of the occupant of the bed.

Referring more particularly to the drawings, 1 represents a mattress body, which may be of any suitable form. We prefer to use our invention with a mattress of the usual construction, consisting of an envelop 2 of suitable material such as mattress cloth, and stuffed with a suitable material 3 such as hair, felt, shavings and the like. We provide a bolster 4 preferably of similar construction, having an envelop 5 of cloth or other suitable material and stuffed with a cushion material 6 which may be of any preferred or common kind.

The bolster 5 at one of the longitudinal sides has a flap 7 which is preferably of the same material as the envelop 5 and extends laterally from the bolster at a point intermediate of the two adjacent side edges. We prefer to form the flap integral with the envelop of the bolster, the flap comprising a double thickness of the fabric forming the envelop. The flap is flexible and is secured to the bolster on a line substantially central with respect to the adjacent side edges. The flap has a plurality of clasp sections 8 adapted to co-act with suitable clasp sections 9 carried by the mattress, removably to secure the bolster and the mattress together. The clasp sections 9 are mounted at an end of the mattress and on a line substantially central with respect to said edges. While we prefer to employ clasps as described it will be un-

derstood that the bolster may be secured to the mattress in any other suitable manner, for instance, by pinning, sewing, by means of hooks and eyes, buttons, and the like.

5 When the bolster is in use as a foot protector the lower ends of the bed covers 10 are inserted between the end of the mattress and the bolster as is shown most clearly in Fig. 3. The bolster when in the operative position 10 indicated in Fig. 3 holds the covers securely in position while at the same time protecting the feet of the occupant of the bed from cold air and drafts. If the bolster is used as a head protector the covers are not inserted 15 between the head of the mattress and the bolster, the bolster merely acting as a shield in this case. As the flexible connection between the bolster and the mattress is intermediate of the upper and lower surfaces of 20 the same the bolster can be operatively positioned at both the upper and lower surfaces of the mattress; that is, the mattress can be reversed without interference by the bolster. When the bed is not in use the bolster can be

arranged between the end of the mattress 25 and the foot of the bed so that the surface of the bed will appear level.

Having thus described our invention we claim as new and desire to secure by Letters Patent:—

In combination, a mattress, a bolster having a flexible flap extending from end to end of a side thereof and arranged intermediate the edges of the side; and means for removably securing said flap to a mattress at an 35 end thereof and intermediate the edges of the end, said flap permitting said bolster to be arranged upon either face of said mattress and at an angle therewith, to form a foot or head protector and to hold bed clothes in position. 40

In testimony whereof we have signed our names to this specification in the presence of two subscribing witnesses.

CHARLES UHDEN.
IRA OWEN.
